UNITED STATES PATENT OFFICE.

HORACE P. OWENS, OF ATLANTA, GEORGIA.

REINFORCED-CONCRETE FENCE-POST AND FASTENER THEREFOR.

1,060,623.

Specification of Letters Patent.

Patented May 6, 1913.

Application filed September 12, 1912. Serial No. 720,062.

To all whom it may concern:

Be it known that I, HORACE P. OWENS, citizen of the United States, residing at Atlanta, in the county of Fulton and State of Georgia, have invented certain new and useful Improvements in Reinforced-Concrete Fence-Posts and Fasteners Therefor; and I do hereby declare the following to be a full, clear, and exact description of the invention, such as will enable others skilled in the art to which it appertains to make and use the same.

This invention relates to improvements in fence posts and is more particularly related to fence posts of the reinforced concrete type.

The object of the present invention is to provide a composite post formed of plastic material which is reinforced to guard the same against breakage, and to increase the strength thereof.

A further object of the invention is to provide a novel form of fastening means for the line wires, the same being anchored in the post, and therefore substantially an integral part thereof, but which are so constructed as to permit "stringing" of the line wires without the necessity of using any special tools or appliances.

With these general objects in view, the invention consists substantially in the novel construction, combination, and arrangement of parts hereinafter fully described, illustrated in the accompanying drawings, and pointed out in the appended claims.

In the drawings: Figure 1 is a perspective view of a fence post constructed in accordance with the present invention. Fig. 2 is a vertical sectional view in perspective through a portion of the post and showing one of the fasteners. Fig. 3 is a side elevation of one of the fasteners used in securing a barb wire in position. Fig. 4 is a top plan view of the same. Fig. 5 is a top plan view of the fastener used in securing a woven fence in position. Fig. 6 is a side elevation of the same.

Referring in detail to the accompanying drawings, the numeral 10 designates the body portion of the herein described post. This is formed of plastic material, preferably concrete, and said body is provided with a reinforcing rod 20 which extends vertically through the body of the post.

Anchored in the body 10 is a series of fasteners 12 for the line wires of the fence.

These fasteners are formed of sheet metal, preferably galvanized steel, and thus susceptible of stamping or bending to the desired configuration. The fastener is formed by bending a straight piece of sheet metal to form a large eye 14, and after this eye is formed the fastener is given a half twist as shown at 15. The ends of the fastener are then placed in a die and clamped down, and the said ends turned inwardly as at 16 to form an entrance 17 for the line wire. By this construction and arrangement the ends or jaws 16 are yielding and have a spring action throughout their entire length so that the line wire can be readily secured in position within the fastener by simply pressing the same in the aperture 17 and forcing the jaws 16-16 apart, which jaws, as soon as the wire is passed into the opening 18, will spring together again so as to completely close the opening, when the wire will seat itself in either one of the recesses 18-18 formed in the jaws or ends 16-16.

An important feature of my invention is the spring action of the jaws along the entire length of said jaws, by which construction and arrangement the line wire can be secured within the fasteners without manipulation of the fasteners other than pressing the line wire against the springs jaws 16-16. The fastener is given a half twist as at 15 in order to have the entrance of the fastener extend parallel with the line wires to facilitate the entrance thereof, and to have the large eye 14 vertical to receive an anchoring rod 20, which extends through the post 10, and engages all of the eyes 14 of the fasteners, and thus holds the same in proper alignment and in position within the post. Another important feature of my fastener is that after the line wires are inserted in the same and the tension device for stretching the wires is removed, the wires are prevented from sagging by the barbs of the wires coming in contact with the sides of the fasteners, the said fasteners simply permitting a relaxation of the wires to this extent so that a tight fence is secured.

Where the fasteners are used in conjunction with a woven fence it is not necessary to give the fasteners a half twist as the fasteners are only employed to receive and retain the vertical strands of such woven wire. In securing a woven fence in position on my improved posts it is only necessary to secure the fencing to one of the posts and

then stretch the same to another post and press one of the vertical connecting wires into the opening 17 between the spring jaws 16—16, whereupon the said wire would be 5 snapped with the fastener and held in position within the same.

From practical experience I have found that I can manufacture these fasteners very rapidly and at slight cost, and that a fence, 10 either barb wire or woven, can readily be secured in position on the posts by means of my improved fasteners without the utilization of any tools, by simply pressing the strands of the wires between the spring jaws 15 of the fasteners, directly in front of the fasteners and in line with the direction in which the fastener extends.

I claim:—

1. A fence post comprising a concrete 20 body, a reinforcing and anchoring rod extending longitudinally therethrough, and a plurality of wire fasteners each looped around said rod and having its ends pro-

jecting beyond the surface of the body and reversely bent to meet terminally and form 25 resilient hooks defining a common entrance throat.

2. A fence post comprising a concrete body, a reinforcing rod extending longitudinally therethrough, and a plurality of metal 30 straps each looped closely around said rod and having its intermediate portions twisted around each other from a vertical into a horizontal plane and embedded in the concrete body, the free ends of said straps projecting beyond the surface of the body and being reversely bent to meet terminally and form resilient hooks defining an intermediate common entrance throat.

In testimony whereof I affix my signature 40 in presence of two witnesses.

HORACE P. OWENS.
